UNITED STATES PATENT OFFICE.

CHARLES F. BEERSTECHER, OF CENTREVILLE, MICHIGAN.

RAILROAD FOOT-GUARD.

SPECIFICATION forming part of Letters Patent No. 606,501, dated June 28, 1898.

Application filed January 26, 1898. Serial No. 668,023. (No model.)

To all whom it may concern:

Be it known that I, CHARLES F. BEERSTECHER, a citizen of the United States, residing at Centreville, in the county of St. Joseph and State of Michigan, have invented certain new and useful Improvements in Railroad Foot-Guards; and I do hereby declare the following to be a full, clear, and exact description of the invention, such as will enable others skilled in the art to which it appertains to make and use the same.

The object of my invention is to provide an improved form of foot-guard for railway-frogs which will prevent the foot of a pedestrian from becoming engaged by and caught between the two converging ends of two rail-sections.

The invention consists of a plate of spring metal secured at one end to a tie or other stationary portion located between the converging ends of two rails, the opposite end of said spring-plate being provided with rollers which will permit of the free longitudinal movement thereof and at the same time prevent the upward movement of the plate and the consequent detachment thereof from the rails.

The invention also consists in the peculiar construction of the spring-plate itself, whereby the end thereof which is attached to the rails may be securely held in place and a fulcrum provided for the free end of said plate.

The invention also consists in other details of construction and combinations of parts, which will be hereinafter more fully-described and claimed.

In the drawings forming part of this specification, Figure 1 represents a plan view of two converging rail-sections with my improved foot-guard applied, a portion of the rails being broken away to show the laterally-extending tongues on the guard which serve as a fulcrum therefor. Fig. 2 is a vertical longitudinal section through the same. Fig. 3 is a cross-section on the line xx of Fig. 1, the same extending through the tie, to which one end of the guard is secured, and showing the recesses between said tie and the bases of the rails. Fig. 4 is a detail perspective view of the guard detached. Fig. 5 is a cross-section on the line yy of Fig. 1, the same extending through the rollers at the forward end of the guard.

Like reference-numerals indicate like parts in the different views.

To show the application of my invention, 55 I have illustrated in the drawings two converging rail-sections 1 1, secured to the ties 2 3, the tie 2 being cut away, as shown at 4, forming recesses lying directly beneath the base of each of the rails 1. Located between 60 the rails 1 1 and secured at one end to the tie 2 is a plate 5, of spring metal, the same constituting my improved foot-guard. The sides of said plate gradually converge from one end to the other, so as to conform to the 65 space between the rails 1 1. At the end of the plate 5 adjacent to its point of connection with the tie 2 the same is formed with outwardly-extending tongues or flanges 6 6, which fit within the recesses 4, formed in the 70 tie 2, the said tongues when in place bearing against the upper surface of said tie and the under surface of the rails 1 1. The said tongues are formed by cutting away the material of the plate, as shown at 7 7, forming 75 a narrow contracted web 8, which extends upwardly at an angle to the flat portion of the spring on which said tongues are formed, as clearly shown in Figs. 2 and 4 of the drawings. Just in advance of the web 8 the spring- 80 plate is formed with a flat portion 9, having laterally-extending tongues or fingers 10 10 thereon, which when the plate is in place rest upon the top surface of the base of each of the rails 1 and constitute a fulcrum for the outer 85 free end of said spring-plate. Just beyond the fingers or tongues 10 the plate is curved upwardly until it reaches a point just beneath or in line with the lower surface of the head of each of the rails 1. The outer free-end of 90 the plate 5 is deflected downwardly, as shown at 11, and is formed with an eye or loop 12, within which is located a shaft 13, having rollers 14 14, mounted upon the outer ends thereof, as clearly shown in Fig. 5 of the 95 drawings. Said rollers are mounted loosely on the shaft 13, and between the inner ends of the hubs thereof is located a coiled spring 15, which tends to urge the rollers outwardly in contact with the inner surfaces of the webs 100 of the adjacent rails 1 1. The periphery of each of said rollers is beveled, as shown, so that it will contact with the top surface of the base and the under surface of the head

of the rail 1. Upon the outer ends of the shaft 13 heads or enlargements 16 16 are formed, which fit within sockets or recesses 17 in the rollers 14 and are adapted to engage 5 shoulders at the inner ends of said sockets for preventing the disconnection of the rollers from the shaft.

That portion of the spring-plate 5 which is secured to the tie 2 is protected by a plate or 10 block 18, which fits upon it and is held in place by bolts, screws, or other analogous devices, which pass through the block 18, the plate 5, and the tie 2.

As thus constructed, it will be seen that 15 when my improved foot-guard is in its normal position, as shown in Figs. 1 and 2 of the drawings, the space between the rails 1 1 is completely covered, and as the said plate will not yield to an ordinary pressure it is impossible for the foot of a pedestrian to be caught 20 between said rails and be held thereby. As a train passes over the rails 1, however, said spring-plate 5 will yield, and as the same is compressed a slight longitudinal movement 25 to the free end thereof will be given. The friction caused by said longitudinal movement is reduced to a minimum by the rollers 14, heretofore referred to. It will also be seen that as the rollers 14 are held outwardly 30 in contact with the adjacent faces of the rails 1 1 and bear against the bases and heads of said rails upward or outward movement of the plate 5 is effectually prevented, while a slight longitudinal movement thereof is permitted.

I am aware that it is not broadly new to provide a foot-guard for frogs or converging rail-sections consisting of a spring-plate incapable of yielding under ordinary pressure, 40 but adapted to be compressed by the weight of a train passing over the rail, and I do not claim such construction broadly; but I am not aware that rollers have been provided in the free ends of such plates which not only 45 permit of the longitudinal movement thereof, but prevent the accidental disconnection of the plate upon the rails by the engagement of said rollers with the under surface of the heads of said rails.

50 What is claimed as my invention, therefore, is as follows:

1. A foot-guard for converging rail-sections, comprising a spring-plate secured at one end to a stationary portion of the road-bed, covering the space between the rails and provided at its opposite end with antifrictional devices.

2. A foot-guard for converging rail-sections, consisting of a plate of spring metal 60 secured at one end to a stationary part of the road-bed, inclosing the space between the rails and provided at its free end with rollers, as and for the purpose set forth.

3. A foot-guard for converging rail-sections, consisting of a plate of spring metal 65 secured at one end to a tie or other stationary

part of the road-bed, deflected upwardly from its point of connection with said tie, and having a flat portion covering the space between the rails, and rollers in the free end 70 thereof bearing against the bases of the two opposite rails, and adapted to engage the lower surfaces of the heads of said rails, as and for the purpose set forth.

4. A foot-guard for converging rail-sections consisting of a plate of spring metal, secured at one end to a tie or other stationary part of the road-bed, deflected upwardly from its point of connection with said tie, having a flat portion covering the space between the rails and provided with a downwardly-deflected portion adjacent to its free end which terminates in a loop, and a double roller whose shank is inclosed by said loop and whose engaging portions bear against 85 the bases of the rails and are adapted to engage the under side of the heads of the rails, as and for the purpose set forth.

5. A foot-guard for converging rail-sections, consisting of a plate of spring metal 90 having a base and flat portion and an inclined web between said base and flat portion, formed by slots or recesses, the said flat portion being provided with laterally-extending tongues or fingers adapted to bear against 95 the upper surface of the base of said rails, and the base of said plate adapted to fit beneath the base of the rails, as and for the purpose set forth.

6. The combination with a pair of converging rail-sections and the ties to which they are secured, one of said ties being cut away forming recesses beneath the bases of said rails, of a foot-guard consisting of a plate of spring metal having a base adapted to fit 105 within the recess in said tie, provided with laterally-extending tongues or fingers adapted to bear against the top surface of the bases of said rails, provided with an inclined portion adjacent to said tongues, and a flat portion lying adjacent to the head of the rails, and covering the space between them, as and for the purpose set forth.

7. A foot-guard for converging rail-sections, comprising a spring-plate secured at 115 one end to a stationary portion of the road-bed, covering a space between the rails and provided at its opposite end with outwardly spring-pressed rollers, as and for the purpose set forth.

8. A foot-guard for converging rail-sections, comprising a spring-plate secured at one end to a stationary portion of the road-bed, covering the space between the rails and provided at its opposite end with a loop, a 125 shaft fitting within said loop, rollers loosely mounted on said shaft, and a spring surrounding said shaft and engaging the adjacent ends of the hubs of said rollers, as and for the purpose set forth.

9. A foot-guard for converging rail-sections, comprising a spring-plate secured at

one end to a stationary portion of the road-bed, covering the space between the rails and provided at its opposite end with a loop, a shaft fitting within said loop having heads or 5 enlargements upon its opposite ends, rollers loosely mounted upon the ends of said shaft and provided with sockets or recesses in which said heads fit, and a coiled spring surrounding said shaft and engaging the inner

ends of the hubs of said rollers, as and for the purpose set forth.

In testimony whereof I affix my signature in presence of two witnesses.

CHARLES F. BEERSTECHER.
